[57] CLAIM

The ornamental design for a wheel, as shown and described.

DESCRIPTION

FIG. 1 is a front elevational view of a wheel showing my new design;

FIG. 2 is a sectional view thereof taken along line 2—2 in FIG. 1;

FIG. 3 is a rear elevational view thereof;
 FIG. 4 is a side elevational view thereof.

FIG. 5 is a fragmentary front elevational view of a wheel showing a second embodiment of my new design, the sole difference being in the addition of five spokes;
 FIG. 6 is a fragmentary rear elevational view of FIG. 5;
 FIG. 7 is a fragmentary front elevational view of a wheel showing a third embodiment of my new design, the sole difference being in the addition of ten spokes;
 FIG. 8 is a fragmentary rear elevational view of FIG. 7;
 The cross-section and side of the embodiments shown in FIGS. 5 through 8 are the same as those shown in FIGS. 2 and 4 of the drawing.
